CATHODE

Marshall C. Pease, Needham, Mass., assignor to
Sylvania Electric Products Inc., Salem, Mass.,
a corporation of Massachusetts

Application August 20, 1948, Serial No. 45,363

4 Claims. (Cl. 250—27.5)

1

This invention relates to cathode construction and particularly to an improved cathode for use in a magnetron.

It has been found in practice that the efficiency and output capacity of a magnetron is substantially adversely affected by stray electrons. It becomes desirable therefore to control and utilize a high percentage of its electron emission and confine the electrons to the space within the tube in which they will perform the useful work of the tube.

It is an object of the invention to provide a cathode which exercises more complete control over its electron emission.

A further object of the invention is to provide a cathode having an improved structure operable to prevent excessive endwise movement of electrons during tube operation.

A further object of the invention is to provide a cathode having operating characteristics which contribute to extremely stable operation of the tube in which it is used.

Other objects and features of the invention will more fully appear from the following description and will be particularly pointed out in the claims.

The illustrative embodiment of the invention may be described briefly as follows. The cathode is of the indirect heater type having a heater element mounted in a hollow cylindrical cathode body member, the heater and cathode body having suitable electrical connections reaching to the outside of the tube. The body portion is provided with a suitable electron-emissive material on its outer surface. The electron-emissive material is confined to the working portion of the cathode which in the type of cathode shown is that portion adjacent the portion of the tube anode sections between which the oscillating field exists.

Without special means it is not possible to confine electron movements to a desired area. Various means have been used to prevent the path of electrons from invading areas where their presence will lower the efficiency of the tube. Partial control of this electron spread has been achieved in various ways. The present invention provides a combination of electron controlling elements including flange-like baffles and axially extending vanes associated with the baffles which substantially eliminate endwise escape of electrons out of the designated oscillating field.

Forces acting upon the electrons create a great deal of turbulence at and beyond the ends of the working portion of the cathode. These forces

2

have a component causing axial movement thereof which if permitted to function cause inefficiency and loss of power output or may cause failure of the tube to oscillate. The present invention prevents this turbulence and thus prevents most of the electrons from escaping into areas where they will impair tube operation.

To provide a better understanding of the invention a specific embodiment thereof will now be described and illustrated in the accompanying drawings in which:

Figure 1 is a cross section of a magnetron embodying the invention.

Figure 2 is a perspective view of a cathode detached from a tube showing the details of the invention as embodied therein.

Figure 3 is a longitudinal sectional view of the cathode.

Figure 4 is a cross section through the cathode taken on line 4—4.

The cathode shown is cylindrical in form and has a hollow metallic body member 1 which is secured within the envelope 2 of the tube in which it is used. The central portion of the cathode 15 is coated with an activating material 3 such as is commonly used to provide a zone of high electron emission.

The emissive material is applied to the cathode at the portion of its body adjacent the resonating portion of anode sections 4 of the tube. The active material 3 supplies the electron flow to support the tube output.

The anode sections 4 constitute the resonator system and are shown as of the interdigital type 35 but may be of any suitable type. The cathode is mounted in position within the tube envelope 2 to supply electrons to the resonator system of the tube. The members 4 have the general contour of a hollow cylinder and the cathode is placed upon the axis thereof within the cylinder.

As shown the cathode is supported upon a rod 5 extending axially therethrough. The rod is mechanically connected to the cathode by insulating collars 6 secured in the ends of the cathode. 45 The rod itself is secured to the envelope 2 by short rod sections the ends of which are anchored in the glass. One rod 7 is led through the glass and serves as the cathode lead of the tube.

A heater coil 8 is situated within the cathode. The heater surrounds but is spaced from the rod 5. One end of the coil is connected to the lead 7 while its other end is led out through a hole in the collar 6 and is welded to a lead 9 fused through the envelope 2. Power for the heater is supplied through the leads 7 and 9.

The emissive material 3 extends along the cathode body 1 for a distance substantially equal to the axial length of the resonating portion of the anodes. A pair of intercepting flanges of annular baffles 10 are formed integrally upon the metallic cathode body and are spaced from the ends of the active coating 3. In addition to the baffles 10, a plurality of vanes 11 are also provided which coat with the members 10 to prevent escape of electrons into the space beyond the resonator elements.

The vanes 11 extend axially along the cathode body from the baffles 10 toward the edge of coating 3 and are desirably substantially the same height as that of the baffles 10. Two such vanes are provided at each end of the active material 3.

The vanes 11 are placed at the nodal planes of radio frequency voltage of the resonator system to avoid disturbing the normal operation of the tube. In the present form of the invention the vanes are thus spaced peripherally 180° from each other. In a different mode of operation of the tube it may be found more effective to provide more than the one pair of vanes 11.

In the operation of such tubes the alternating magnetic field set up thereby causes electrons on one side of the nodal plane to be accelerated axially in one direction and on the other side to be accelerated in the opposite direction. As a result of this action a substantial tendency exists for electrons to reach the space beyond the fingers of the resonator anodes. If a substantial amount of electrons do reach this area the efficiency of the tube is lowered.

The combined effect of the baffles 10 and the vanes 11 act to trap the electrons and prevent their axially outward travel thus increasing the tube output capacity, its efficiency and stability of operation.

What I claim is:

1. A cathode comprising an elongated metallic body member, a coating of electron emissive material on a portion of said body member, annular metallic flange-like baffles extending around said body member and spaced from the ends of said coating, said baffles being substantially larger than the transverse dimension of the body member, and vanes on the cathode disposed axially thereof and extending from each baffle toward the ends of the coating whereby outward axial movement of the electrons beyond the baffles is prevented.

2. A cathode comprising an elongated metallic body, electron emissive material covering a por-

tion of the length of said body, external flange-like metallic baffles extending around said body and projecting outward therefrom, said baffles being spaced from the ends of said coated portion of the body and at least one pair of substantially flat vanes extending along said body from said baffles toward the ends of the coated portion of the body and situated in a longitudinal central plane through said body.

10 3. A cathode comprising a hollow cylindrical metallic body member, a coating of electron emissive material covering a zone of said body member, annular metallic baffles surrounding and projecting a substantial distance outward from said body member, said baffles being spaced from each end of said emissive coating, a pair of substantially flat vanes at each end of said coating situated 180° apart upon the periphery of said body member and extending lengthwise thereof from said baffles toward the ends of said emissive coating, and heater means within said body member.

15 4. A magnetron device having a pair of resonating anode portions and an envelope for enclosing the tube elements, a cathode secured in said envelope comprising a body portion, an electron emissive coating covering a zone of said body portion, annular baffles extending outward from the periphery of said body portion and spaced from the ends of said emissive coating, and at least one pair of substantially flat vanes on said body portion and extending from said baffles toward the ends of said emissive coating, said vanes being situated in the nodal planes of radio frequency voltage of said resonating anodes.

35 5. MARSHALL C. PEASE.
